(57) **CLAIM**

The ornamental design for a tip for holding an adjustable-angled brush, as shown and described.

DESCRIPTION

FIG. 1 is a perspective view of a tip for holding an adjustable-angled brush, showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The present ornamental design is for a tip for holding an adjustable-angled brush of a cosmetic wand, for example a mascara wand. The tip has slots at a top portion thereof so that the brush can be adjusted stably at various angles desired by a user.
